UNITED STATES PATENT OFFICE.

REUEL S. ROWE AND GEORGE WEINLE, OF RUTLAND, VERMONT.

RUBBER RETAINER.

Application filed September 14, 1922. Serial No. 538,252.

To all whom it may concern:

Be it known that we, REUEL S. ROWE and GEORGE WEINLE, citizens of the United States, residing at Rutland, in the county of Rutland and State of Vermont, have invented certain new and useful Improvements in Rubber Retainers; and we do declare the following to be a full, clear, and exact description of the invention, such as will enable others skilled in the art to which it appertains to make and use the same.

This invention relates to a retainer for use in connection with rubbers and one object of the invention is to provide a retainer which may be suspended from the top of the ordinary leather shoe and may have gripping engagement with the rear portion of the rubber, so that the rubber will be prevented from slipping downwardly and off of the shoe in going through muddy places. It often happens that when going through muddy places, the rubber will stick and will pull off from the heel portion of the shoe but with this device in place, the rubber will be firmly held in place and cannot slip off.

The gripper for engaging the upper portion of the rubber and the suspending hook which is to engage the top of the leather shoe are connected by a yieldable connection and it is desired to have this yieldable connection so constructed that when one portion has become worn, the connection may be moved to bring a new portion into engagement with the hook and gripper.

This invention is illustrated in the accompanying drawing, wherein:

Figure 1 is a view in side elevation showing the device in use.

Figure 2 is a view showing the device in elevation.

Figure 3 is a longitudinal sectional view through the device.

This device is to be used to retain the heel portion of the rubber 1 in place upon the leather shoe 2 and prevent the heel portion of the rubber from pulling off when going

through muddy places. This device is provided with a gripper having jaws 3 and 4 which are provided with pivot ears 5 connected by a pivot pin 6 upon which a spring 7 is mounted. The arms 8 of this spring engage the handle portion of the two jaws and will serve to yieldably retain the jaws in a gripping position. The handle portion of one jaw is provided with a transversely extending slot 9 through which is passed a strip 10 formed of elastic fabric. This strip of elastic fabric is also passed through a slot 11 formed in the shank portion of the hook 12 and the two ends are then sewed together to provide a continuous loop. It will thus be seen that when the device is in use, the loop may have sliding movement through the slot and the wear will be evenly distributed instead of coming upon one portion at all times. From an inspection of Fig. 1, it will be readily seen that when the device is in use, the hook 12 is engaged with the top of the shoe 2 and the heel portion of the overshoe engaged by the gripper. The rubber will thus be firmly supported.

We claim:

A rubber shoe retainer comprising a shoe gripping element having gripping jaws movable into and out of a gripping position, one of said jaws being provided with a transversely extending slot, a shoe engaging element for engaging the upper edge of the rear portion of a shoe, said hook being provided with a transversely extending slot, and a strip of elastic material having its end portions passed through said slots and brought together and connected to provide an endless loop slidably passing through the slots and providing a yieldable connection between said shoe engaging element and gripping element.

In testimony whereof we have hereunto affixed our signatures.

REUEL S. ROWE.
GEORGE WEINLE.
